UNITED STATES PATENT OFFICE.

ANDREW J. TAYLOR AND MILO A. HAMILTON, OF FRANKFORT, KANSAS.

CHURN-DASHER.

SPECIFICATION forming part of Letters Patent No. 252,335, dated January 17, 1882.

Application filed September 10, 1881. (Model.)

To all whom it may concern:

Be it known that we, ANDREW J. TAYLOR and MILO A. HAMILTON, of Frankfort, in the county of Marshall and State of Kausas, have 5 invented certain new and useful Improvements in Churn-Dashers; and we do hereby declare that the following is a full, clear, and exact description of the invention, which will enable others skilled in the art to which it appertains 10 to make and use the same, reference being had to the accompanying drawings, which form a part of this specification.

The object of this invention is to provide a 15 churn-dasher by means of which air can be forced into the cream during the operation of churning, thereby greatly facilitating the process of making butter. This object we attain by means of the device hereinafter described, and illustrated in the annexed drawings, in 20 which—

Figure 1 is a side elevation of the churn-dasher, and Fig. 2 is a central longitudinal section of the same.

The dasher comprises a tubular body, A, having at its lower end a perforated conical shell, B. The tubular body has an enlarged upper end, a, to which is fitted a cap, C, having a central perforation, c, through its top. Said upper enlarged end, a, has an annular seat or 25 flange, a', at its upper portion, and upon this seat is arranged an annular disk carrying a downwardly-opening valve, D, which is hinged to said disk d, having a central opening some-

what smaller than the valve. A strap, d', secured to this annular disk, passes below the valve, so as to limit the downward movement of the same. Within said cap a is also arranged a washer, E, to prevent leakage, and also a fine wire-gauze disk, F, which will preclude the entrance of dust to the valve. As 35 the dasher is raised the valve will open and air will enter its tubular body to supply the vacuum created. When, however, the dasher descends the resistance of the inclosed body of air will close the valve, and hence the air 40 will be expelled from the lower end of the dasher, and, passing out through the perforations of the lower conical end of the dasher, 45 will thoroughly impregnate the cream.

What we claim is—

The churn-dasher comprising a tubular body having a perforated conical lower end, and an enlarged upper end provided with a perforated screw-cap, in combination with the valve and the wire-gauze disk inclosed within the cap at 50 the said upper enlarged end, substantially as 55 described.

In testimony that we claim the foregoing as our own we have hereto affixed our signatures in presence of two witnesses.

ANDREW J. TAYLOR.
MILO A. HAMILTON.
